UNITED STATES PATENT OFFICE.

HELGE A. BORRESEN, OF MARQUETTE, MICHIGAN.

TURRET-PLIERS.

1,110,528.

Specification of Letters Patent. Patented Sept. 15, 1914.

Application filed October 14, 1907. Serial No. 397,329.

To all whom it may concern:

Be it known that I, HELGE A. BORRESEN, a citizen of the United States, residing in the city of Marquette, in the county of Marquette and State of Michigan, have invented 5 a new and useful Turret-Plier, of which the following is a specification.

My invention relates to improvements in pliers, in which the jaws are provided with 10 a number of coöperating or complementary tools for punching, setting or otherwise working material, and the objects of my invention are, first, to provide such pliers in a more simple and economical form, and 15 second, to provide in such pliers ready means for adjusting the coöperating or complementary members in a suitable relation to each other. I attain these objects by the mechanism illustrated in the accompanying 20 drawings, in which,

Figure 1 is a side elevation of the complete tool, Fig. 2 is a detail of the jaw, provided with the transversely revolving turret, Fig. 3 is a sectional view of the jaw provided 25 with the cylindrically revolving turret, and Fig. 4 is an end view of the mechanism shown in Fig. 3, showing the means I employ for ascertaining or locating the various tools in their proper position.

Similar reference figures refer to similar parts throughout the several views.

I employ any usual form of parallel plier designated by the reference numeral 1, upon one jaw of such a plier I produce the slot, 2, 35 and through the walls of the slotted portion I provide the arbor, 3, upon which is adapted to revolve the wheel like portion, 4, the ends of the spokes of which I form into suitable punches and dies for the work to be 40 performed by the tool. In order to ascertain and fix the position of the respective dies or punches, I provide upon the side of the jaw the spring, 5, attached to said jaw by means of the screw, 6, and carrying on its 45 other end the lug, 7, which protrudes through a portion of the jaw and projects into one of the recesses, 8, provided in the spokes of the wheel, 4; the other jaw of the plier I form into the rod, 10. Surrounding 50 this rod, 10, is the cylinder, 11, having the enlarged recess, 12, therein to hold the spring, 13. The outer end of the cylinder, 11, is provided with a series of notches, 14, and transversely through the rod, 10, is provided 55 the pin, 15, which is adapted to engage the proper notches, 14, when the spring, 13,

forces the cylinder outwardly. These notches or recesses 14 may be triangular in cross-section as apparent in Figs. 3 and 4 so as to present what amounts to a cam surface 60 abutting the pin 15, to thereby automatically aline the cylinder. To cover the notches, 14, and the end of the rod, 10, I provide the cap, 16.

Projecting radially from the periphery of 65 the cylinder, 11, I provide punches and dies, 17, which are adapted to work in combination with or to be complementary to the punches or dies upon the wheel portion, 4. I have shown in the illustration special dies 70 for putting the cover on main spring barrels of watches. These dies are designated by the numeral, 18. It is necessary that these dies shall extend slightly beyond the edge of the cover for the barrel. Inasmuch as 75 various sized barrels are used in the market, I have provided four different sizes upon the cylinder, 11. It is intended that the periphery of the recesses in each die shall have a different diameter. 80

From the foregoing description, taken in connection with the drawings, it is evident that I provide a tool of multiple uses, of extremely simple construction.

Having described my invention, what I 85 claim as new and desire to secure by Letters Patent, is:

1. A pair of pliers having coöperating jaws, a cylinder mounted longitudinally upon one of said jaws and adapted for rotation thereon, a plurality of cup shaped dies extending from the periphery of said cylinder, and a plurality of tools extending from the periphery of said cylinder. 90

2. A pair of parallel pliers having a jaw, 95 a member extending longitudinally thereover and rotatable thereon, a plurality of tools extending from the periphery of said member and located at different distances from the fulcrum of said pliers, a second jaw provided with a plurality of rotatably mounted tools complementary to the tools carried by the said first mentioned member, said last aforesaid series of tools being rotatable in the plane of said second jaw, and means for adjusting said last mentioned tools in proper relation to said first mentioned tools, so as to aline therewith at all positions of the jaws. 100

3. A device of the class described having 110 jaws, a plurality of tools associated with one of said jaws, a plurality of dies also associ-

ated with said jaw, means upon which said tools and dies are mounted, said means being rotatably mounted about said jaw to rotate about an axis longitudinally of said 5 jaw, and means coöperating with said tools and dies mounted on the other jaw.

4. A pair of pliers having coöperating jaws, a cylinder mounted longitudinally upon one of said jaws and adapted for rotation thereon, a plurality of tools extending from the periphery of said cylinder, a plurality of dies also extending from the periphery of said cylinder, and a plurality of rotatably mounted tools on the other jaw 10 to coöperate with the first aforesaid tools.

5. A pair of pliers having coöperating jaws, a cylinder mounted longitudinally upon one of said jaws and adapted for rotation thereon, a plurality of tools extending 15 from the periphery of said cylinder, and a plurality of rotatably mounted tools on the other jaw to coöperate with the first aforesaid tools, the tools mounted upon said second jaw being rotatable in the central plane 20 of the jaws.

6. In a pair of parallel pliers, a pair of jaws, and a plurality of tools and dies mounted on each jaw in coöperative relation, the pairs of tools and dies aforesaid 25 being located at unequal distances from the fulcrum of said pliers, the pair of dies aforesaid being adapted to coöperate and being cup-shaped, and the tools aforesaid being adapted to coöperate with each other.

30 7. In a pair of parallel pliers, a pair of jaws, and a plurality of tools and dies

mounted on each jaw in coöperative relation, the pairs of tools and dies aforesaid being located at unequal distances from the fulcrum of said pliers, the pair of dies 40 aforesaid being adapted to coöperate and being cup-shaped, and the tools aforesaid being adapted to coöperate with each other, at least one of said tools forming one of a plurality of rotatably mounted adjustable 45 series of tools.

8. A pair of pliers having coöperating jaws, a cylinder mounted longitudinally upon one of said jaws and adapted for rotation thereon, a plurality of tools extending 50 from the periphery of said cylinder, and spring controlled means to automatically aline said cylinder whereby the respective tools are forced into their predetermined alined positions.

9. A pair of pliers having coöperating jaws, a cylinder mounted longitudinally upon one of said jaws and adapted for rotation thereon, a plurality of tools extending 55 from the periphery of said cylinder, and spring controlled means to automatically aline said cylinder whereby the respective tools are forced into their predetermined alined positions, said means including a pin and cam-shaped recesses.

In testimony whereof I hereunto subscribe my name in the presence of two witnesses.

HELGE A. BORRESEN.
